UNITED STATES PATENT OFFICE.

GOUVERNEUR CEALES RHOER, OF LITTLE ROCK, ARKANSAS.

UMBRELLA-LOCK.

1,270,054.

Specification of Letters Patent. Patented June 18, 1918.

Application filed July 31, 1917. Serial No. 183,779.

To all whom it may concern:

Be it known that I, GOUVERNEUR CEALES RHOER, a citizen of the United States, residing at Little Rock, in the county of 5 Pulaski, State of Arkansas, have invented certain new and useful Improvements in Umbrella-Locks; and I do hereby declare the following to be a full, clear, and exact 10 description of the invention, such as will enable others skilled in the art to which it appertains to make and use the same.

This invention relates to staff sockets for umbrellas, and has particular reference to sockets in which a staff may be located.

15 The object of the invention is to provide an improved form of device for receiving and locking into place the staff of an umbrella of that type which is used upon carriages and wagons and is generally mounted 20 upon the driver's seat. More particularly my invention consists in the provision of a socket within which a staff may be locked, a suitable key controlled locking device being mounted at the side of the socket which 25 is key controlled to prevent or permit the removal of the staff.

With the above objects in view and such others relating to the details of construction as may hereinafter appear, my invention 30 will now be fully set forth and described, reference being had to the accompanying drawings:—

In the drawing:—

Figure 1 is a side elevation of the device 35 in use,

Fig. 2 is a vertical section through the entire device,

Fig. 3 is a section on line 3—3 of Fig. 2, and

40 Fig. 4 is a section on line 4—4 of Fig. 2.

Referring more particularly to the drawings, 1 represents a tubular socket of suitable depth to properly support and brace the end of a staff 2 which, in the present instance is the end of an umbrella standard, though it may obviously be any similar or analogous device. The standard is mounted either upon a base or on the back of a carriage or other vehicle seat in an obvious 45 manner. At its lower end, the socket is internally provided with a coil spring 3 whose lower end is secured in position, and whose convolutions provide a cushion for the lower end of the staff 2. Vertically secured to, or formed on the interior surface 50 of the socket is a rib 4 which preferably

extends through the length of the socket, and coöperates with a corresponding groove cut into the staff 2, so that the latter is prevented from rotation within the socket. 60 Upon the staff 5, at a point within the limits of the portion which fits within the socket 1, is a lug or knob 5 which is preferably located diametrically opposite the groove 4, said lug being adapted to appear opposite 65 a vertical slot of short duration which is formed in the wall of the socket 1, the lug appearing opposite the socket when the staff is pressed downwardly to compress the spring in the bottom of the socket. The slot 70 6 provides an entrance for a latch 7 which is formed upon the lower end of an arm 8. The arm 8 is a continuation of a coil spring 9 which is mounted to rock upon a spindle 10 having its bearings in the walls of a 75 lock casing 11 which is suitably bolted or clamped to the inside of the socket 1. The spring 9 tends to throw the latch into the opening or slot 6 so that it may normally be positioned to snap into engagement above 80 the lug 5 when the staff is pushed downwardly in the socket. A leaf spring 16 secured to the side of the casing also tends to throw the arm 8 into position. Above the spindle 10, the spring 9 is continued in a 85 spring arm 12 which is positioned to be engaged by the head of a key 13 when the latter is projected through the key slot 14. The head of the key 13 is shaped with a cam face 15 which is adapted, when the key 90 is projected through its key slot to tension the spring arm 12, so as to withdraw the latch 7 from the slot 6, when the key is drawn into vertical position, it again releases the spring arm. Obviously, when 95 the key is removed, the spring arm stands free to permit the latch to project into locking position.

In the use of my device, the standard 3 may be dropped into the socket, and supported upon the head of the spring cushion in freely removable relation. However, when pressure is exerted on the staff to shove it down within the socket, the spring 19 is compressed, and the latch 7 is snapped 100 above the lug 5. In order to release the latch 7 from the lug, so that the staff may be removed, the key is employed in the manner above described. It should be remembered that the lug 5 may be substituted 105 by a notch in the staff into which the latch 7 is projected.

It will be apparent from the foregoing that I have provided a simple and practical device for securely holding a staff in position against accidental or unauthorized removal, and that the device may be readily applied to vehicle seats or bodies without great expense or labor.

What I claim as my invention is:—

- A staff socket, comprising in combination,
10 a tubular element, a spring cushion in the body of said element, a vertical rib formed longitudinally throughout the length of the socket, a staff adapted to seat within the socket element and having a vertical groove
15 to coöperate with said rib to prevent rotation of the staff, a lock casing mounted upon the socket element, a transverse pin extending across the casing, a spring latch mounted on said pin and having an end

projecting through the wall of the socket element, said latch consisting of a spring wire element coiled to provide a bearing to receive the transverse pin, an upwardly projecting member to coact with a key, a downwardly extending element carrying said projecting end, and a spring to force the downwardly extending element toward the wall of the socket element, a key for controlling the spring latch, and a lug provided on the staff for engagement by said latch when the staff is depressed in the socket element against the action of said spring.

In testimony whereof, I affix my signature in the presence of two witnesses.

GOUVERNEUR CEALES RHOER.
